UNITED STATES PATENT OFFICE.

TIODOLF LIDBERG, OF CHICAGO, ILLINOIS, ASSIGNOR TO CHICAGO SURGICAL & ELECTRICAL CO., OF CHICAGO, ILLINOIS, A CORPORATION OF ILLINOIS.

ELECTROTHERMOSTAT.

1,169,549.

Specification of Letters Patent.

Patented Jan. 25, 1916.

Application filed May 19, 1914. Serial No. 839,619.

To all whom it may concern:

Be it known that I, TIODOLF LIDBERG, a citizen of the United States, residing at Chicago, in the county of Cook and State 5 of Illinois, have invented certain new and useful Improvements in Electrothermostats, of which the following is a specification.

My invention relates to improvements in electrothermostats.

10 One of the general objects of my invention is to improve the accuracy and sensitivity of thermostats to control electric circuits.

15 One of the special objects I have in view is to provide a thermostat that is reliably sensitive and positively operable within very small changes of temperature, whereby the temperature of the atmosphere within an incubator, such as is used for bacteriological 20 purposes, may be maintained substantially constant.

25 The air within an incubator used for the propagation of bacteria must at all times, be maintained at an equable temperature. A variation of a few degrees will destroy or stunt the germs and render the incubator useless for the purpose intended. Therefore, a reliable heat-response and controlling means, operated by the heat which it 30 controls, must be sensitive, quick of action, without lag either way and dependable.

35 A better understanding of my invention may be obtained from a consideration of the following description, when taken in connection with the drawing, wherein;

40 Figure 1 is a plan view of the thermostat; Fig. 2 is a central vertical section, taken on line 2—2 of Fig. 1. Fig. 3 is a transverse section, taken on line 3—3 of Fig. 1.

In all the views the same reference characters are employed to indicate similar parts.

45 The device, as depicted in the drawing, is of such size as to give very practical results. The body portion consists of two flanged rings 5 and 6 secured around their periphery, as by screws 7, of which there may be any desirable number. Between the outward projecting flanges, 8—8 of said rings, 50 is included the heat responsive diaphragm, generally indicated by 9, consisting of a sheet of material having a high co-efficient of expansion, such as hard rubber 10, and a sheet of hard drawn copper, bronze or the like, 11, or any other suitable material hav-

ing a lower expansive heat coefficient. The sheets or disks are held together, as by two circumferentially extending rows of rivets, 12 and 13, and around their periphery they are bound together, by the screws 7 and 14, 60 which pass through the two flanged rings 5 and 6 and through the composite diaphragm. The screws 14—14 also pass through brackets, 15, upon which to support the device, on the walls or the floor of the incubator. One 65 of the brackets is provided with an electric terminal screw, 16, by means of which the copper disk 11 may be connected in an electric circuit by screws passing through the perforations 17—17. A bar 18 is transversely fixed across the diameter of the diaphragm and insulatedly supported by screws 19, which pass through the rings 5 and 6 and the diaphragm 9. An electric terminal screw 20 is threaded into the end of the bar 70 18 to which one terminal of the electric circuit may be connected. An adjustable screw 21 is threaded through the bar 18, near the longitudinal center thereof, and is provided on its inner end with a contact 22, adapted 80 for co-operative relation with the contact 23 of the metal disk 11 of the diaphragm. A friction brake, for the purpose of maintaining the screw 21 in its adjusted position, consists of a spring 24, bearing upon the face 85 of the screw 21, and secured to the bar 18, as by screws 25. This spring has frictional bearing with the screw and maintains it in whatever position it may be placed, the adjustment of the screw being necessary to 90 change the degree of temperature to be maintained.

The device is to be placed within an incubator, with an electro-responsive means for producing heat, which the thermostat is adapted to control. In many instances an incandescent lamp is used for the purpose and connected in series with the device, the heat of the incandescent lamp being more than sufficient to maintain the atmosphere at the desired temperature, when the lamp is uncontrolled by the thermostat. 95

100 Normally the electric circuit is completed between the contacts 22 and 23 and the lamp is burning. Now when the lamp has supplied heat sufficient to bring the interior temperature of the incubator up to the desired point, the outer disk 10, of hard rubber, will expand to a greater extent than the inner metal diaphragm 11 thereby caus-

ing the composite diaphragm 9 to be deflect-
ed near its central zone, to the right or
dished outwardly, so that the movable con-
tact 23 is carried away from the relatively
5 stationary contact 22, the circuit is opened
between the contacts and the lamp will be
extinguished. The slightest chilling of the
atmosphere, less than one quarter of a de-
gree in practice will cause the diaphragm
10 10 to be contracted to a greater extent than
the diaphragm 11, and the parts will be re-
turned to circuit-closing position, and the
lamp will thereby be again lighted so that
it will raise the surrounding atmosphere to
15 its normal temperature. The device is so
sensitive that there is a trembling connec-
tion between the contacts 22 and 23 and
therefore the lamp is rarely caused to burn
at its normal rated capacity.
20 A condenser may be connected between
the contacts 22 and 23 to subdue the sparks,
if it is found necessary, in fact; however,
where a single incandescent lamp, requiring
25 not over half an ampere, is used I have
found the spark between the contacts to be
so small as to become practically negligible
without the use of a condenser.

Turning the adjusting screw 21 clockwise
will have the effect of pressing the dia-
phragm 9 outwardly and therefore it will
30 require a greater heat, within the incubator,
to cause separation of the contacts 22 and
23 than when the pressure produced by the
screw against the diaphragm is not so great,

and consequently the critical temperature 35
to be maintained may thus be varied.

It is manifest that other means than the
rivets 12 and 13 may be employed for con-
necting the disks of the diaphragm together,
but it is essential that they should be main-
tained in intimate contact between their
40 centers and their peripheral edges, so that
in every instance they may be moved to-
gether and not susceptible of separate or in-
dependent movement. 45

Having described my invention, what I
claim is:—

A device of the character described com-
prising two flanged diaphragm supporting
rings; a diaphragm comprising a hard rub-
ber disk and a metal disk clamped together
50 at their peripheries, between said rings;
means for securing said disks together with-
in the area inclosed by said rings; an elec-
tric contact near the center of said dia-
phragm, movable therewith; an insulated
bar crossing said diaphragm and secured to
said rings; and an adjustable contact car-
ried by said bar for electric coöperation
55 with the contact relatively movable by said
diaphragm. 60

In testimony whereof I hereunto set my
hand in the presence of two subscribing wit-
nesses.

TIODOLF LIDBERG.

In the presence of—
FORÉE BAIN,
MARY F. ALLEN.
